UNITED STATES PATENT OFFICE.

DANIEL P. KELLOGG, OF LOS ANGELES, CALIFORNIA.

TIE-PLATE.

1,367,551.

Specification of Letters Patent.

Patented Feb. 8, 1921.

Application filed July 31, 1920. Serial No. 400,302.

To all whom it may concern:

Be it known that I, DANIEL P. KELLOGG, a resident of Los Angeles, in the county of Los Angeles and State of California, have 5 invented a certain new and useful Improvement in Tie-Plates, of which improvement the following is a specification.

My invention relates to means for connecting railroad track rails to the cross ties 10 on which they are supported, and its object is to provide an appliance of the class known as "tie plates", which shall be of simple and inexpensive construction, and ready application in superstructure of standard type, 15 and will attain the substantial advantages of preventing "creeping" and lateral displacement of the rails, and minimizing deterioration of ties by effecting a distribution of the weight applied thereto.

20 The improvement claimed is hereinafter fully set forth.

In the accompanying drawings: Figure 1 is a plan or top view of a portion of a railroad track rail and of three cross ties to 25 which it is connected, illustrating an application of my invention; Fig. 2, a side view, partly in longitudinal section, on the line *a a* of Fig. 1, of the same; Fig. 3, a transverse section, on the line *b b* of Fig. 1; and, 30 Fig. 4, a plan view, on a reduced scale, of a blank from which the tie plate is formed, before being cut and bent into the form in which it is applied.

In the practice of my invention, referring 35 descriptively to the specific embodiment thereof which is herein exemplified, I provide a tie plate, 1, which is formed from a rectangular piece of boiler plate of suitable thickness and width, by cutting and bending on its sides and ends, as indicated in Fig. 4, the dotted lines indicating those of bending, and the full lines those of cutting. The tie plate herein shown is adapted for 40 the connection of a rail, 2, of standard section, to three cross ties, 3, 3, 3, and, to this end, the blank for the plate is made of a length equal to the distance over the three ties, plus sufficient distance, as say, two inches or thereabouts, to enable a flange, 1^a, 45 to be turned down at each of its ends, to abut on the outer side of the tie at that end. The blank is also notched or cut out, on each 50 of its sides, in the spaces between the ties, thereby forming lateral recesses, 1^b, at each 55 end of which recesses, a downward flange, 1^c, adapted to abut on one side of a tie, is

turned. The tie plate is secured to the ties by spikes, 4, and the rail is laid upon it, and secured to it, by having its bottom flanges fitted under clips, 1^d, formed by turning 60 over the metal of the plate to fit the rail flanges, one of said clips being located in one of the recesses, 1^b, on one side of the rail, and the other being located in the other recess, 1^b, on the opposite side of the rail. The 65 rail and clips are secured by nut-equipped bolts 5.

It will be seen that the tie plate above described performs the functions of an anti-creeper, a rail anchor, and a spacer which 70 holds the rails in gage in both directions, and it also acts to preserve the ties to a considerable extent, as it prevents the whole weight on any wheel from being applied to a single tie, by reason of the fact that if a tie 75 should be deflected, the tensile strength of the plate is exerted to impose weight on the connected ties and effect its distribution. The rail could not move out of gage without carrying the connected ties, or shearing 80 the clips, that are bent over the rail flanges. In order to turn over, it would be necessary for the rail to bend the clip portion of the plate, or turn over the entire plate, with its broader base, or bend it at 85 the edges of the rail flanges, which would hardly be possible through three sections of channel.

I claim as my invention and desire to secure by Letters Patent:

1. The combination of a railroad track rail; a plurality of cross ties; an interposed integral plate metal tie plate, spanning the ties and having a plurality of transversely extending flanges, abutting both sides of 95 each tie, and longitudinally extending, oppositely disposed clips, engaging the opposite flanges of the rail; means for positively securing the rail to the clips; and means for positively securing the tie plate to the ties. 100

2. The combination of a railroad track rail; a plurality of cross ties; an interposed integral plate metal tie plate, spanning the ties and having a plurality of transversely extending flanges, abutting both sides of 105 each tie, and longitudinally extending, oppositely disposed clips, engaging the opposite flanges of the rail; bolts, securing the rail to said clips; and spikes, securing the tie plate to the ties.

3. A tie plate formed from a rectangular sheet of plate metal, of sufficient length

to span a plurality of cross ties, and having downwardly turned end flanges, each adapted to abut on one side of a tie; lateral recesses, each having downwardly turned 5 end flanges, adapted to abut on the adjacent sides of two ties; and upwardly turned clips, in said recesses, adapted to engage a rail

flange, and located on alternately opposite sides of the plate.

DANIEL P. KELLOGG.
